UNITED STATES PATENT OFFICE

WILLIAM INTEMANN, OF BROOKLYN, NEW YORK, ASSIGNOR, BY MESNE ASSIGNMENTS, TO INTERNATIONAL BANDING MACHINE COMPANY, A CORPORATION OF NEW YORK

METHOD AND MEANS FOR PLURALITY BANDING

Application filed March 16, 1929. Serial No. 347,486.

The principal object of this invention is to apply a strip formed of a plurality of bands simultaneously to each of the individuals of a group of articles of merchandise, and wrapping the bands individually partly about the articles, during such wrapping the multiple strip being severed into the requisite number of bands.

My invention is particularly adapted to the application of a multiple strip formed of a number of short bands united end to end in a single strip, to multiple merchandise, as for instance foil wrapped cigars, the strip being picked from a storage box, gummed, and presented to multiple merchandise, the strip divided into individual bands which are wrapped partly around the article of merchandise.

The invention relates broadly to the art of simultaneously banding the individuals of a multiple group of articles of merchandise by placing a strip comprising a multiple band upon the members composing the group, then severing the strip into units, and finally setting the unitary bands.

Novel mechanism which is useful in carrying out or practicing this method or art in its preferred form embodies means moving downwardly toward a suitable work holder for placing a gummed strip formed of a number of bands upon an equal number of articles supported by the holder and during the continuance of such movement wrapping the bands individually about the articles. After the initial placing of the strip and while this is held in proper position on the articles by the pressure of wrapping and the tenacity of the gum the strip is cut into its component bands.

In the drawings forming part of this application one practicable embodiment of mechanism which I invented and designed for use in practicing my improved method is illustrated, in which drawings Figure 1 is a top view, partly broken away, of one form of my machine, showing the picker head located over the stack of multiple bands and a plurality of cigars supported in the work holder.

Fig. 2 is a longitudinal section of the ma-

chine with the parts illustrated in the Figure 1 position. This section is taken on a line which passes in front of the gummer behind the work holder and through the center of the cam wheel.

Fig. 3 is a broken away top view showing the picker arm and picker head swung to an angle of about 90° from the Figure 1 position over the work holder and in the position of applying the bands to the cigars.

Fig. 4 shows the face of the cam wheel, a view being taken from the left hand side of Figs. 1, 2 and 3.

Figs. 5, 6 and 7 are detail views showing some of the positions of the picker, arriving at the working point of the machine, carrying a multiple band strip, Fig. 5, preliminarily placing the strip upon the group of articles of merchandise, Fig. 6, completing the operation of wrapping the individual bands about the individual articles of merchandise after the strip has been severed, and

Fig. 8 is a perspective view showing one of the banded articles.

While it is apparent that this invention may be employed in connection with applying bands of various lengths having varying numbers of bands united end to end in a single strip to a similar number of articles of merchandise, yet for convenience of illustration I have represented a work holder designed for taking a group of two articles to which a multiple strip composed of two bands is applied. And while the invention may be practised in connection with various articles of merchandise, it is particularly designed for applying short and half labels to foil wrapped cigars.

By analogy to the familiar bands which are completely wrapped about many of the cigars now on the market for carrying trade names, etc., the labels illustrated herein are termed "bands", although wrapped only partially around the cigar. The claims are intended to cover the art of and the mechanism for wrapping bands or labels of selected length more or less fully about the cigar.

The work holder 9 herein is shown standing from a suitable frame base 10 and

formed with a plurality of suitably shaped pockets 11 for holding the required number and character of articles of merchandise to be banded, in the present instance two cigars 12.

5 The work head or picker 13 is shown carried by an oscillatory arm 14, the picker arm, which has a hub 15 splined to a rotary shaft 16. This shaft is shown having a head 17 disposed below the plate of the base frame 10 and mounted in an upstanding bushing 18 having a flange 19 secured to the upper faces of the plate 10. Suitable means presently to be described are employed for raising and 10 lowering the hub 15 and for rotating it by means of rotation imparted to the shaft 16.

15 The supply of strips 20 is properly located on the machine frame by means of a plurality of pins 21 suitably arranged. The strips are 20 fed upwardly and are cushioned by means of suitable springs 22. Each of these strips 20 comprises a plurality, in the present illustration two, of bands 23 united end to end in the multiple strip, and which in the present design are intended to be wrapped half way around the individual articles of merchandise, the foil covered cigars 12.

25 In the passage of the picker from the Figure 1 position to the Fig. 3 position, it passes 30 the gumming station 24 which in the present illustration comprises a gum applying roller 25.

35 The work holder is shown provided between the work receiving pockets or recesses with an upstanding knife blade 26. The work head or picker head 13 is provided with a suitable face 27 for cooperation with the knife 26 in severing or shearing the strip.

40 The work head or picker is given arch shaped formation on its lower side at 28 for the purpose of pressing and wrapping the bands about the articles being operated upon. In the illustration there are two of these arch shaped applicators, each of which extends into a pair of feet 29 which have their surfaces preferably located in the same plane. The arches are shown with an air chamber or 45 suction chamber 30, such chambers leading by means of a pipe 31 to some suitable suction apparatus. Mechanism for oscillating the picker head 13 and picker arm 14 comprises a segmental gear 32 fast with the shaft 16, which gear is moved in opposite directions by means of a rack bar 33 mounted at 50 one end in the slide 34 and at the other in the slide or guide 35.

55 Power is furnished in some suitable manner to a driving shaft 36, one end of which is shown mounted in a bearing 37 carried by a 60 bracket 38 supported on the bed plate 10. To this shaft there is shown keyed a cam wheel 39 having in its periphery a cam groove formed of several parts, 41, 42, 43 and 44, presently to be referred to in detail, in which 65 is received a roller 40 carried by one end of a

bell crank lever 45, the other end of such bell crank lever carrying an upstanding pin 46 which engages a pair of lugs 47 formed on the rear of the rack bar 33.

70 The hub 15 which carries the picker arm 14 is provided with a circumferential groove 48 for the engagement of rollers 49 carried by the arms 50 of a rocker lever 51 pivoted at 52 to an arm 53 upstanding from the bed of the machine. The other end of the lever 51 carries a roller 54 which runs in a cam groove 75 in the face of the cam wheel 39, this groove having portions 61, 62, 63 and 64, whose functions will presently be described.

79 After the picker has been caused to descend upon the top strip in the stack 20, and to have engaged it by means of the suction created in the chamber 30 and applied to the faces of the feet by means of suitable openings 55, it is slightly raised and passed over the roller 25 85 at the gumming station. It is thereafter presented above the work holder and caused to descend, wrap the strips around the cigars, severing the strip 20 into its units 23, then rise clear of the cigars and pass again to a 90 position over the stack, but this time at a sufficient height to clear the gum applying means.

95 The peripheral cam groove, i. e. the groove in the periphery of the cam 39, presents a straight portion 41 which permits or assures a dwell in the oscillation of the picker arm over the stack. At this time the portion 61 of the cam groove in the face of the wheel lowers the work head to pick up a strip, and raises the head with the strip thus picked up. The portion 62 of the cam holds the work head or picker head on the proper level to pass the strip 20 which it carries across the gummer wheel 25. This portion of the oscillation is effected by means of the regularly formed portion 42 of the cam groove. A straight portion 43 of the cam groove permits a dwell in the picker head at the working point of the machine during the function of the portion 63 of the other cam, which presses the picker toward the work holder and raises the head above the work pieces after the bands have been applied, and to the level of the circular portion 64 of the groove which maintains the picker head at a sufficient height or level to permit it to pass above the gummer, the clear oscillation for the return of the picker arm to the starting point being afforded by the cam portion 44.

105 A cam portion 43 permits a sufficient dwell for the cam portion 63 to move the picker arm from the Fig. 5 position through the Fig. 6 position to the Fig. 7 position, and back to the Fig. 5 position before the active portion 110 44 of the cam shifts the rack bar 33 from its Fig. 3 position to its Figure 1 position.

115 By again referring to Figs. 5, 6 and 7 it will be seen that the gummed strip is presented well above the work pieces, the cigars 120

12, so that there will be no smearing of the gum. The head still carrying the multiple strip descends to a position where it places the center of each of the individual bands upon a cigar. Further movement of the picker head causes the cutter 26 to cooperate with the cutting face 27 in shearing or severing the strip into its units. The accuracy of the cutting operation is facilitated by the tendency of the gum at the point of application and the preliminary wrapping which has taken place, together with the secure holding of the strip by the suction means. During the cutting or severing operation the wrapping continues until it is completed. The picker head then rises to a sufficient distance to completely clear itself from the work, whereupon the return movement above described is effected.

It will be apparent that changes in detail may be made within the scope of the claims without departing from the spirit of my invention.

I claim:

1. That improvement in the art of banding merchandise, which consists in handling a multiple band as a unit, first from a stack to a gumming station, then placing the gummed multiple band onto the multiple merchandise, then severing the band into units and finally setting the unitary bands.
2. That improvement in the art of banding merchandise, which consists in handling a multiple band as a unit, first lifting the multiple band from a stack, then placing it as a unit upon the multiple merchandise, then severing the band into units and finally simultaneously setting the unitary bands.
3. Means for concurrently individually applying a multiple band strip about a plurality of cigars, and comprising a work holder for presenting a plurality of cigars simultaneously at the working point, a picker head adapted to pick up a multiple band strip, means for gumming the strip, means mounted on the work holder for severing the band, and means for moving the picker head for effecting the severance of the strip into bands and the wrapping of these about the cigars.
4. The combination with a work holder, having means for presenting a plurality of work pieces in proper position for concurrently receiving bands from the work head, a band severing device located between the work piece positions, of means for holding a stack of one piece multiple band strips, a work head constructed and adapted to pick up the uppermost strip of the stack and present it at the working point and partly apply it to the work pieces, such work head having cooperative band severing means for severing the strip into individual bands upon such partial application, and then to wrap the individual bands about the work piece.
5. Means for concurrently individually applying a multiple band strip about a plural-

ity of cigars, and comprising a work holder for presenting a plurality of cigars simultaneously at the working point, a picker head adapted to pick up a multiple band strip, means associated with the work holder and 70 picker head for severing the band, and means for moving the picker head for effecting the severance of the strip into bands and the wrapping of these about the cigars.

6. Means for individually and concurrently wrapping a multiple band strip about a plurality of cigars and comprising a work holder constructed and adapted to support a plurality of cigars at the working point of the machine, a picker head formed with a 80 number of arch-shaped pressing surfaces equal to the number of cigars which the work holder is adapted to support, the picker being formed with a shearing surface, a cooperative shearing member carried by the work holder between cigar positions, means for holding a stack of strips, a gumming device, and mechanism for actuating the picker embodying a cam wheel having a groove formed with cam faces for effecting the oscillation of the picker and for causing a dwell when it is at the stack and when it is at the work holder, and said cam wheel having a second groove having cam faces for effecting the lowering of the picker onto the stack, raising it and passing it over the gumming device, and lowering the picker onto the stack, and raising it during the first mentioned dwell to a plane at which it is effective to present a picked up strip to the gumming device during the forward excursion of the picker, and depressing the picker toward the work holder, and raising it during the second mentioned dwell to a plane at which it may freely pass the gumming device in its return.

In witness whereof, I hereby affix my signature this 12th day of March, 1929.

WILLIAM INTEMANN.
